WILLIAM LAFAYETTE QUICK, OF NEW MARKET, ALABAMA.

FLYING-MACHINE.

1,076,644.

Specification of Letters Patent.

Patented Oct. 21, 1913.

Application filed February 9, 1912. Serial No. 676,494.

To all whom it may concern:

Be it known that I, WILLIAM L. QUICK, a citizen of the United States, and a resident of New Market, in the county of Madison 5 and State of Alabama, have invented a new and Improved Flying Machine, of which the following is a full, clear, and exact description.

My invention relates to flying machines, 10 and it comprises a new and improved construction of this sort in which great strength and lightness are combined with perfect elasticity, and the constituent parts of which are so arranged as to give automatic stability to the entire apparatus, while at the 15 same time permitting any manual adjustments which, in the judgment of the aviator, may be required.

It is an object of this invention to provide 20 a flying machine, preferably of the heavier-than-air type, in which the framework is built in such a way as to give a perfect stream-line form to the body of the airship, so as to diminish as far as possible the 25 resistance opposed by the air to the travel of the airship.

Another object of this invention is to provide 30 an airship provided with laterally-extending wings or lifting planes patterned after the outline and profile of the wings of soaring birds. These wings are attached to the front part of the body by a ball-and-socket joint, and likewise attached to the body to the rear of the front part by means 35 of additional pivotal connecting means, so as to permit the compound adjustment thereof. As a result of joining the wings to the body in this fashion, each of the wings can be adjusted around two axes, one of said axes 40 extending longitudinally of the wing and the other transversely thereto; and suitable means are provided for effecting the adjustment in question as the same may be required, according to the varying conditions 45 which are met with in flight.

A further object of my invention is to provide 50 a flying machine having a tail plane which acts as a rudder to cause the machine to ascend or descend, this rudder being controlled by connections extending to points 55 adjacent the aviator's seat; and likewise provided with a vertically-disposed rudder adjacent the tail plane, also controlled by connections adjacent the aviator's seat to steer the machine from right to left whenever a turn is to be made.

A still further object of my invention is to provide a flying machine of the kind mentioned having the driving means distributed over the entire width of the machine, so as 60 to avoid the localizing and concentrating effect that is obtained when a single propeller placed in central position forward or aft of the body of the airship is employed.

Reference is to be had to the accompanying 65 drawings forming a part of this specification, in which the same characters of reference indicate the same parts in all the views.

Figure 1 represents a top plan of my flying 70 machine; Fig. 2 represents a front elevation thereof; Fig. 3 represents a transverse vertical section taken on the line 3—3 of Fig. 1, and looking forward; Fig. 4 represents a longitudinal sectional view of the 75 airship; Fig. 5 represents a top plan of the driving connections for the propellers; Fig. 6 represents a front elevation thereof; Fig. 7 represents a sectional view on the line 7—7 of Fig. 6; Fig. 8 represents an end elevation 80 of one of the blades to which power is applied to propel the airship; and Fig. 9 represents a modified form of wing, showing a construction by means of which the wing can be folded when not in use. 85

Referring particularly to the drawings, the numeral 1 represents four curved longitudinal bars or rods which form the body of the framework of my airship. These bars are curved to have a stream-line form, and 90 they may be covered with cloth or light sheets of metal to inclose the interior of the framework, if desired. The four bars or rods 1 are united at their ends by socket-shaped coupling members 2; and to plates 95 carried by these coupling members are joined the ends of a diamond-shaped frame made up of elastic cables 3, which are separated from each other by means of a transverse central bar 4. This frame is thus elastic, 100 and it can be tilted to one side or the other for a purpose which will appear later.

The numerals 5 represent the wings or lifting planes which are of course covered with suitable fabric to make a continuous 105 surface; and the numeral 6 represents the tail plane at the rear of the framework. Power is applied to drive the airship by means of oscillatable propeller blades 7, mounted in bearings adjacent the centers of 110 the forward edges of the wings and extending outward substantially as far as the wing

tips; and 8 represents similar oscillatable propeller blades which are mounted on either side of the longitudinal axis of the framework of the aeroplane and extend outward toward the axes of oscillation of the blades 7 aforesaid. The tail plane 6 can be tilted around a horizontal transverse axis so as to cause the aeroplane to ascend or descend; and beneath the tail plane 6 is a rudder 9, mounted to turn around a vertical axis to direct the airship to the right or left whenever a turn is to be made.

The numeral 10 represents a transversely-arranged bar supported by the lower pair 15 of longitudinal bars 1, and forward of the center of the machine as disclosed in Fig. 4. The outer ends of this bar are bent downward and are given the form of yokes shown at 10', in which are mounted wheels 11. The 20 bar 10 is received in bearings in the end of resilient longitudinal members 13 carried upon the two lower bars 1, and these resilient members 13 are further supported by springs 14, to add to the cushioning effect of the 25 members 13; and the bar 10 is further provided with a pair of arms 15 having pedals formed thereon, by means of which the aviator can rotate the bar 10 with his feet, so as to swing the wheels 11 up to the level of 30 the lower bars 1, when the machine is in flight.

16 is a wheel located at the rear end of the body of the framework of the airship, and is mounted in a yoke 17 secured to a 35 shaft 17'. This shaft 17' is mounted in a vertical bearing made integral with the rear coupling 2; and the ends of the base of the yoke 17 are pivotally connected to operating cords or rods 19, which extend forward, and 40 are pivotally secured at their opposite ends to the ends of a bar 20, pivotally secured to a shaft 21, but held against longitudinal movement thereon. This shaft is supported at its lower end in a transverse member 22 45 carried by the lower pair of bars 1, and has its top 23 pivotally connected, as by means of a ball-and-socket joint, to the transverse bar 4. Any form of pivotal connection between the members 4 and 21 may be used 50 which will not interfere with the transverse tilting movement of the bar 4. To the bar 20 is fixed an arm or lever 24, which is designed to be engaged by the knee of the aviator, so as to turn the cross-bar 20 and 55 thus turn the wheel 16, so as to guide the aeroplane when the same is moving forward over the surface of the ground before rising into the air.

So long as the results above mentioned 60 are obtained, it does not matter in what manner the cords or rods 19 are connected to be operated by the arm or lever 24. For example, I may mount the rod 21 so as to be rotatable, securing the same pivotally to 65 the bar 22, and by a ball-and-socket joint to

the cross-bar 4; and in this case I may fix the cross-bar 20 upon the shaft 21, and fix the arm 24 to the shaft 21 in the same way; or, as described, I may mount the shaft or support 21 in the bar 22, so as to hold the 70 shaft 21 against rotation, and connect it to the bar 4 by means of any form of joint that will permit the bar 4 to tilt transversely. In such a case, the cross-bar 20 must be pivotally connected to the support 21, but held 75 against downward movement thereon, as by collars above and below the same; and the arm or lever 24 must be fixed to the bar 20, but likewise pivotally mounted upon the shaft or support 21. 80

The wing frames comprise bent transverse rods 25 which form the front edges thereof, and these rods 25 are connected at their inner ends to ball-and-socket joints made integral with the forward coupling 85 2. The edges of the wings adjacent the body of the framework are shown at 27, and the longitudinal ribs for the wing frames are shown at 28.

29 represents tension stringers which extend from the strips 27 across the ribs 28 to the rods 25, and are secured to all of the parts mentioned to increase the strength and stiffness of the wings.

30 represents plates which are secured to 95 the top of the wing frames adjacent the mid points of the rods 25 forming the front edges of the wings. They are provided with lugs 31 upon the opposite sides of outwardly-extending recesses in the edges of 100 these plates, and these lugs are perforated to serve as bearings for the outer propeller blades 7. Each of the plates 30 projects beyond the forward edge of the wing on which the same is mounted, and the recesses are 105 formed in the outer edge of each of the projecting portions, as shown in Fig. 1, so as to enable the outer propeller blades 7 to clear the edges of the wings when the propellers are in motion. The rear edges of the plates 110 30 are provided with a pair of alined lugs 32, which extend upward from the plane of the plates; and these lugs are perforated to receive a pivot-pin which connects the plates to main lever arms by means of which 115 the wings are tilted to raise or lower the outer tips of the wings when necessary. It will be seen that the ribs for the outer half of the wings all center in the plates 30 and are secured thereto. This gives strength to 120 the wings. These main lever arms are shown at 33. They are pivotally connected to the plates 30 by means of the lugs 32, and the pins passing through the same; and the pins in question and the ball joints 26 are 125 substantially in the same transverse line with one another. This will appear from an inspection of Fig. 1. Each of the levers 33 has a lug 33^a projecting from its rear edge adjacent the strips 27 at the base of the 130

wing; and these lugs are perforated to receive screws 33^b. These screws are screw-threaded at their lower ends and engage corresponding screw-threaded sockets in the strips 27, so that the distance between the strips 27 and the levers 33 can be adjusted. If desired, the screws 33^b may simply be rotatably connected to the strips or rods 27, and held against longitudinal movement 10 with respect thereto; and they may be threaded adjacent the portions which pass through the lugs 33^a. This will be another manner of adjusting the rods or strips 27 forming the inner edges of the wings, with 15 respect to the main levers 33, by turning the screws 33^b.

The lever arms 33 are secured to the steel cables 3 by means of plates 34, which pass under the steel cables 3 and are secured to 20 the bottom of the arms 33 by means of screws or bolts which pass into the lever arms 33 at points located outside of each pair of cables on either side of the diamond-shaped frame of which they form a part; 25 and at their inner ends the arms 33 are pivotally connected to a belt or chain 35, which passes over an upper and a lower pulley 36. The belt or chain 35 is so mounted upon the pulleys 36 as to prevent slipping relatively thereto. The upper pulley 36 is mounted in a bearing 37 by means of 30 a shaft 38 supported by the bearing, and having a boss 39 at its forward end which is perforated to permit the shaft 38 to be 35 pivotally connected to a transverse shaft 40, mounted upon the two upper bars 1 near the forward ends thereof. The shaft 38 is thus held against rotation, and the upper pulley 36 is loosely mounted thereon. The 40 lower pulley 36 is mounted upon a shaft which is carried by a bearing 41, which has telescoping engagement with the bearing member 37; and 42 represents a spring inside the bearing member 37, which normally 45 forces the members 37 and 41 away from each other and keeps the belt 35 under proper tension. 43 represents a pair of tension springs connected one to each of the two upper bars 1, and to the bearing member 50 37. By means of this construction the pulleys 36 are supported at a proper height above the two lower bars 1.

44 represents a cross-bar to be actuated by hand, secured to the rear edges of the 55 upper pulley 36.

45 represents a similar bar to be operated by the aviator's feet, secured to the lower pulley 36. These two operating bars are connected by means of a link 46, so as to be 60 operated in unison.

Extending from the upper surface of each of the wings 5 at the point of connection between the rods 25 and the bars 27 are arms 47; and the numerals 48 represent 65 guide wheels secured to the top surfaces of

the two upper bars to receive a steel cable 49. This steel cable is joined at its opposite ends to the arms 47, and when the portion between the two upper bars 1 is pulled, both the wings 5 are caused to rotate in 70 unison around their forward edges to depress their rear edges, as will be readily understood.

The numerals 50 represent main guys, each of which is secured at its outer end to 75 the under side of one of the main levers 33, and is held spaced therefrom by means of braces 50' secured to the outer ends of the plates 34 and extending downward, as shown in Fig. 3. The inner ends of the 80 guys 50 are secured to tension springs 51, which pass through the body of the framework above the two lower bars 1, and are joined by means of adjustable connections, so that the tension on these springs can 85 be regulated. In order to regulate the tension of the springs 51 I connect each to a threaded socket into which screws a bar having threaded portions on its opposite ends, so that, when the bar is turned, the 90 sockets will be drawn nearer to each other or moved in the opposite direction, as will be readily understood, the sockets to be held against movement of course when the bar is being turned; but I may also use an ordinary turn-buckle for this purpose if desired. The object of the tension springs 51 is to hold the wings at a certain inclination, with the tips thereof slightly higher than the inner edges adjacent the forward half 95 100 of the diamond-shaped frame supported by the body of the framework made up by the longitudinal bars 1.

The tail frame for my improved airship comprises a transverse bar 52, to which is 105 secured a semi-circular hub 52'. This semi-circular hub serves as a base or support for radiating ribs 53; and the outer ends of the transverse bar 52 are connected by means of braces 54 to the upper bars 1, 110 so as to prevent the tail plane 6 from rotating around a horizontal longitudinal axis.

55 is a central operating bar for the tail frame, secured at its rear end to the transverse bar 52 and the semi-circular hub 52', 115 and extending forward, as shown in Figs. 1 and 4; and this operating bar is pivotally mounted at 56 upon the upper end of the shaft 17', which supports the rear wheel 16, so as to permit the tail plane 6 to be tilted 120 up and down.

At its front end the bar 56 is connected by means of a pivot 57 to an arm 58, and this arm 58 is rigidly secured to the upper rear edge of the aviator's seat 59. This seat has 125 lugs 59' projecting from the back of the same, and these lugs are perforated to permit the transverse bar 4 to pass therethrough. The lugs may be arranged on either side of the center line passing 130

through the back of the aviator's seat, and may be connected by means of a tubular sleeve, as shown in Fig. 4, this tubular sleeve to be recessed simply on its under side to 5 permit the support or shaft 21 to pass through to be joined to the bar 4, as previously described. By means of this construction, whenever the aviator tilts the seat forward or backward, the tail plane will 10 be raised or lowered, owing to the pivotal connection of the operating bar 56 with the arm 58 rigidly secured to the aviator's seat. Secured to the lower side of the operating bar 55 is a bracket 60, which extends downward 15 beneath the same and has a bearing in its outer end for a shaft or spindle 61. This spindle is likewise pivotally secured at its upper end to the central rib 53 of the tail plane 6, and it serves as a support for the 20 framework of the rudder 9. This rudder is kite-shaped, and its front end is connected to a tension spring 62, which is joined to the bar 56 adjacent its junction with the bracket 60, to hold the rudder 9 in longitudinal position. Secured to the spindle 61 is a cross-bar 63, and to the ends of this cross-bar are 25 attached operating rods or cords 64, pivotally connected at their forward ends to a transverse rod 65, which passes across the top of the operating bar 55, adjacent the 30 pivotal connection of the same with the arm 58. To this cross-bar 65 are likewise pivotally connected a pair of links 66, and these links are pivotally joined at their front 35 ends to a bar 67, pivotally secured to the back of the seat 59. The ends of this bar 67 terminate in forward-extending arms 68. The bar is held against longitudinal movement with respect to the seat 59, but can 40 rotate around the back of the seat 59 whenever it is actuated by the aviator's shoulders, regardless of the position of the seat 59, so that, by tilting the seat 59, forward or back, the tail plane 6 is controlled, and by twisting 45 the shoulders or upper part of the body so as to move them against the arm 68, the cross-bar 67 is controlled to actuate the rudder 9.

The numeral 69 represents a supporting 50 framework for the centrally-located driving means, and this supporting framework is preferably made integral with the forward coupling 2 of the body of the frame of the airship. The framework in question comprises a pair of circles 70, one of which is horizontal and the other of which is vertical and longitudinal, as shown, and the horizontal circle has a bearing 71 in its front end, which receives the power shaft 72, the 55 forward coupling member 2 having a bearing extending forward therefrom to permit the shaft 72 to pass.

The numeral 73 represents a sprocket chain connecting the shaft 72 to the crank

shaft of the motor 74; gear wheels being 65 mounted on the ends of the shaft 72 and the crank shaft of the motor for this purpose.

The vertical circle 70 has a pair of guides 75 mounted therein, and these guides engage a head 76, which has shoes 77 projecting therefrom which enter grooves 78 in the opposed faces of the guides 75. The head 76 is in the form of a circle, and it is provided with a pair of transverse guides 79, which receive a sliding block 80 between 75 them. This block 80 is mounted upon a crank pin 81 carried by a crank 82 upon the shaft 72, and as the shaft 72 rotates, the block 80 slides in the guides 79, and the head 76 slides in the guides 75, moving up 80 and down, as will be understood. The head 76 has a circumferential groove 83 in its outer face to receive an operating cord or cable by which power is transmitted therefrom.

The horizontal circular frame 70 has laterally-located journals on which are mounted to oscillate pulleys 84, having grooves 85 and 86 in their outer faces. To the front face of these pulleys are secured elastic ribs 87, which may be made of steel or any other 90 sufficiently strong material; and these ribs 87 taper from the pulleys to the points thereof, and are curved as shown in the drawings. To them are secured the webs which form the surfaces of the propellers; and normally the ribs 87 will be curved so as to lie in a horizontal plane, as shown in Fig. 8.

88 represents an operating cable passing from the head 75 into the grooves 85, on the pulleys 84, and this operating cable will be 100 secured to the head 76 to prevent it from moving in the groove 83. Consequently, as the head 76 moves up and down, the pulleys 84 will be caused to rotate through a certain angle, and the inner propellers 8 will 105 oscillate in consequence.

Pivotedly mounted in the plates 30 on each of the wings 5 are the outer propeller blades 7, which comprise ribs 91, similar to the ribs 87, and to these ribs are secured 110 the webs of suitable material forming the surfaces of the propellers. The pulleys 90 are made rigid with the ribs 91, and are mounted between the lugs 31 carried by the plates 30, and connected by means of operating cables 89 to the inner pulleys 84.

The manner of operation of my aeroplane will now be described. The aviator will take his seat in the chair 59 and place his feet upon the lower bar 45. The inclination 120 of the wings 5 from the front edge to the back edge will be determined by the screws 33^b; and when the engine is set in motion, the propellers 7 and 8 will be vibrated to set the machine in motion. As the head 76 moves down in the guide 75, the propellers 7 125 will move upward and the propellers 8 will move downward; and when the head 76 moves up

ward, the direction of motion of the propellers 7 and 8 will be reversed. Owing to the fact that the ribs 87 and 91 of the propellers 7 and 8 are curved in horizontal 5 planes, and owing to the fact that these ribs are elastic, the ends of these ribs will bend downward when the propellers move up, and upward when they move down; and the result will be a thrust from the front to the 10 back, whichever way the propellers may be moving to furnish motive power for the airship. This action is shown on Fig. 8.

The aviator can control the ascent and descent of the machine by manipulating the 15 tail plane 6, simply by tilting the seat 59 forward or backward, and he can guide the airship to the right or left by moving his shoulders against the arms 68 and manipulating the rudder 9 whenever a turn is to be 20 made.

While moving over the surface of the ground, the direction of motion of the airship is controlled by means of the lever 24 operating the rear wheel 16. After the airship has once risen from the ground and has begun its flight, the pedals 15 are operated to swing the front wheels 11 up into the body of the framework, as will be readily understood.

30 The angle at which the wings 5 are inclined from the front edge to the back edge can be altered by taking hold of the steel cable 49 between the wheels 48 and pulling on the same. This will lower the rear edges 35 of the wings 5. This operation is useful in slowing or stopping the machine, and by increasing the head-on resistance to its motion. The rear edges of the wings 5 can likewise be depressed by pressing down simultaneously upon the bar 44 and the bar 45, so as to depress the inner ends of the main 40 lever arms 33. Owing to the elasticity of the cables 3 which form the sides of the diamond-shaped frame, this action will result in lowering to some extent the rear 45 ends of the bars 27, and thus increase the inclination of the planes, as will be readily understood. At the same time, when both the inner ends of the arms 33 are depressed, 50 the outer ends of the wings 5 will be tilted up. The flexibility of the steel cables 3 is another feature of construction which permits the wings to have their rear edges lowered when necessary, by means of the cable 55 49, because, when this cable is pulled to rotate the wings around their front edges, the rear edges are depressed and the inner ends of the beams 33 are depressed to some extent with it; and the steel cables 3 may yield 60 to a sufficient extent to permit this action. If desired the screws 33^b may simply have screw-threaded engagement with the lugs 33^a on the arms 33, without being attached to the rods 27. They will then serve as adjustable bumpers spacing the rods 27 from

the arms 33 a certain distance without holding the rods 27 fast to the arms 33. Whenever the wings are then adjusted by means of the cable 49, they will simply be rotated around axes passing through the lugs 70 32, and the ball and socket joints 26, and the steel cables 3 forming part of the diamond-shaped frame will not have to yield in this case. By pressing down upon both ends of the bars 44 and 45, the inner ends of the main lever arms 33 can be depressed so as to raise the outer wing tips, the cables 3 yielding for this purpose; and by pressing down upon one end of the bars 44 and 45, the tip of one wing can be raised and the other lowered.

I wish to call especial attention to the utility and function of the elastic diamond-shaped frame supported by the bars 1. This frame automatically stabilizes the machine, 85

because it can be tilted from side to side and thus change the angle of incidence of the air current against the under surface of the wings. As the angle of incidence for one wing is increased, the angle of incidence for the other wing is automatically decreased. The triangular frame has normally a horizontal position which it retains and in which it operates to hold the wings in proper position until changed by some 95 external force, either by the operator or some unbalanced force or pressure against the wing. For example, if the right wing is struck by a puff of air that would disturb the lateral stability of the machine by forcing the right side too high, the elastic joint provided by the ball 26 would instantly allow the wing to spring upward, thus tilting the triangular frame to some extent through the elastic cables 3, and thus diminish the angle of 100 incidence of the right wing in this way. At the same time, the cross-bar 3 would be tilted upward on the right and downward on the left, and this would increase the angle of incidence for the left wing which is now lower than the right wing, and restore the machine to a horizontal position.

This is because, when the right wing is tilted upward by an unbalanced puff of air, the arm 33 attached to the right wing rotates around its inner end as an axis, tilting up the frame on its right side and lowering it on the left side. As the left side of the frame sinks it of course pulls the left lever arm 33 down with it, and warps the left wing to a greater extent. This gives a greater upward reaction of the air on the left side of the machine and brings the entire airship back to horizontal position. Further, as stated above, by means of the 110 main lever arms 33 and the manner of controlling their inner ends, the wing tips can be raised or lowered, causing them to be higher than the inner edges or lower than the inner edges, while the surfaces of the 115 120 125 130

wings remain at all times inclined from their front edges to their back edges. The dihedral angle thus formed by the front edges and inner longitudinal edges of the wings can thus be changed from positive to negative at will. The dihedral angle will be positive when the wings have their tips higher than the frame 3, and negative when their tips are lower than the frame.

From the above description it will be apparent that the wings are attached to the body of the framework of the aeroplane in such a way as to be adjustable around transverse and longitudinal axes; that is to say, they can be adjusted about an axis passing through the lugs 32 and the balls 26 to regulate the inclination from the front edge to the rear edge, or adjusted about axes corresponding to the bars 27, to increase the inclination of the wings in the direction of the tips thereof. By adjusting the wings around the transverse axis which passes through the lugs 32, and ball-and-socket joints 26, the machine can be stopped or made to slow down, and head-end plunges averted; and by tilting the wings around axes passing through the bars 27, by means of the main levers 33, the dihedral angles made by the front and inner longitudinal edges of the two wings can be altered as stated above. This is important, as by increasing the dihedral angle, that is, by tilting the tips of the wings upward, while retaining the same amount of inclination thereof from the front to the rear edge, the machine is made more stable, and flies slower; and as the angle is diminished by lowering the wing tips, the machine tends to fly faster, because the angle of incidence is also slightly diminished. This is because, when both the inner ends of the arms 33^b are allowed to rise at once, they lift up the bars 27 with them, thus raising the lower ends of these bars and diminishing the inclination of the wing surfaces in consequence.

Fig. 9 represents a modification of the wing frame. In this figure the wing frame is shown as provided with two rods 92 and 93, which are connected by means of a hinge joint comprising sections 94^a and 94^b. The section 94^b is pivotally connected by means of lugs to the main arm 33; and the wing itself comprises two sections, the inner forward corner of the outer of which carries the hinged section 94^a, and the outer forward corner of the inner section of which carries the hinged section 94^b. As stated above, these two sections are secured together to form a hinge, as by means of a pivot-pin; and the hinged section 94^a has secured thereto a bent bar 97, which forms the inner edge of the outer wing section. The inner wing section has a diagonal bar 98 extending from the bent bar 93, forming

the forward edge of the inner section, rearwardly, and this bar 98 is connected by means of a stringer 96 to the bar 27. A similar stringer 95 connects the bent bar 92, forming the forward edge of the outer section, to the bar 97, as shown. The bar 97 is not straight, but its forward portion makes an angle with the bar 98, and its rear portion is parallel therewith. When the bars 97 and 98 are disconnected from each other, the outer section of the wing can be rotated around the pin connecting the hinged sections 94^a and 94^b, to fold the two sections together; but when the two sections are distended and the rear half of the bar 97 secured to the adjacent portion of the bar 98, the two sections will be rigid with each other, forming a wing that is ready for use.

From the above description it will be apparent that I have produced a superior construction for purposes of aerial navigation. The body is composed of only four curved bars and four steel cables united to a cross-bar to make up the diamond-shaped elastic frame, and thus forms a support for a complete housing for the operator, with a stream-line form when the longitudinal bars 1 are covered as above described. The head-end resistance of the machine is very small, and the elasticity of the parts is perfect without detracting from their strength. The entire apparatus is automatically stabilized; and this holds true with respect to both lateral and longitudinal tilting; and the arrangement of the propellers in front distributes the driving power instead of concentrating it, as would be the case if only one central propeller were used.

I wish to have it understood that the foregoing description and drawings are illustrative only, and disclose but one embodiment of my invention, and that I do not wish to be limited to the details herein shown, except in so far as is indicated in the accompanying claims.

Having thus described my invention, I claim as new and desire to secure by Letters Patent:

1. In a flying machine, the combination of a framework, a rudder carried thereby and extending rearward therefrom, a vertical spindle to which said rudder is secured, a cross bar carried by said spindle, a pair of rods pivotally secured on the ends of said cross bar and extending forward, a seat for the aviator pivotally mounted on the framework, a horizontal cross arm pivotally mounted upon said seat, means for pivotally connecting said forwardly extending rods to the ends of said cross bar of the aviator's seat, and shoulder engaging portions secured to the cross bar on the aviator's seat to enable the rudder to be

manipulated by the movement of the aviator's body.

2. In a flying machine, the combination of a framework, a pair of lifting planes pivotally secured adjacent the inner ends of their front edges to said framework, means carried by said framework and engaging said planes to hold said planes in inclined position, and means secured to the front edges of said planes adjacent the inner ends thereof and extending to a point within reach of the aviator for increasing the inclination of said planes.

3. In a flying machine, the combination of a framework, laterally extending lifting planes pivotally secured to said framework, a lever arm for each of said lifting planes extending outwardly from said framework in position to engage the inner end of the plane and pivotally secured to the said plane at its outer end, and means for raising and lowering the inner ends of said lever arms to raise or lower the tips of the planes.

25 4. In a flying machine, the combination of a framework, a cross bar carried thereby, flexible means connecting the ends of said cross bar to the front and rear of said framework, lifting planes for said flying machine, means for pivotally connecting said lifting planes adjacent the inner ends of their forward edges to said framework, and a pair of lever arms secured to said flexible means forward of the cross bar and extending outward from the framework in opposite directions, each of said lever arms being connected to one of the planes at its outer end, whereby when one of the planes is struck by an unbalanced air puff disturbing the lateral stability of the machine, the frame formed by the cross bar and flexible means will likewise be tilted laterally, depressing the rear edge of the other plane and causing the said other plane to rise, owing to the increased upward reaction thereon, thus restoring the machine automatically to a level position.

5. In a flying machine, the combination of a framework, a pair of wings or main planes pivotally secured adjacent the inner ends of their forward edges to the framework, a pair of arms carried by said framework to the rear of the forward edges of the wings and extending therefrom in opposite directions, means pivotally securing the outer ends of each of said arms to one of said wings, the axis of said pivotal securing means being in line with the means for pivotally connecting the wings to the frame, and means carried by each of said arms between its ends and engaging the framework of the wings adjacent their inner longitudinal edges for increasing or decreasing the inclination thereof whereby the

slope of the lower surface of each of the wings may be adjusted.

6. In a flying machine, the combination of a framework, comprising a pair of outwardly curved longitudinally extending bars joined together at their front and rear ends, lifting planes pivotally connected adjacent the inner ends of their forward edges to the front of said framework, a quadrangular shaped body having flexible sides carried by said framework and joined to the opposite ends thereof, said flexible sides being held separated by means of a cross bar adjacent the middle of the body, a pair of levers secured to the sides of said flexible body and extending outward in opposite directions from said framework, means for pivotally securing the outer ends of each of said levers to one of the planes, the axis of said pivotal securing means extending in the direction of the means for pivotally securing the planes to the frame, a pair of pulleys mounted in said framework, a belt passing over said pulleys, means for pivotally connecting the inner ends of said levers to said belt, means for mounting said pulleys to enable the same to be moved bodily upward and downward, and means for manipulating said pulleys to enable the tips of the planes to be raised or lowered at will.

7. In a flying machine, the combination of a framework, a pair of main wings pivotally secured to said framework, means secured to the wings adjacent their forward edges and extending rearward to enable the angle of inclination of said wings to be increased by the aviator, and a pair of lever arms carried by the framework and extending laterally outward therefrom and in opposite directions, said arms being yieldably supported at their inner ends on the framework, and being pivotally connected at their outer ends to the wings, whereby when the inner ends of said arms are moved, the tips of the wings can be raised or lowered.

8. In a flying machine, the combination of a framework and lifting planes supported thereby, a pair of pulley wheels mounted adjacent the front end of said frame, a vibratable propeller blade carried by each of said pulley wheels, and means mounted between said pulley wheels and connected to each of said wheels and movable to transmit motion to said propeller blades.

9. In a flying machine, the combination of a framework having lifting planes carried thereby, a pair of pulley wheels carried forward of said framework, each of said pulley wheels having vibratable propeller blades carried thereon, a pulley wheel mounted between said first-mentioned pulley wheels, flexible means for connecting said first-named pulley wheels to said last-men-

tioned pulley wheel, said flexible means being fixed to all of said pulley wheels, and means for imparting bodily motion to the last-named pulley wheel to cause said propeller blades to vibrate.

10. In a flying machine, the combination of a framework, lifting planes supported thereby, a pair of pulleys supported forward of said framework, a propeller blade secured to each of said pulleys, a third pulley mounted between the first-named pulleys, means for flexibly connecting said pulleys together, said means being fixed to all of said pulleys, means for moving said central pulley to transmit motion to the first-named pulleys to cause the same to oscillate, a second pair of pulleys mounted on the said lifting planes adjacent the forward edges thereof, a vibratable propeller blade secured to each of said second pair of pulleys, and means for flexibly connecting each of the second pair of pulleys to one of the first pair of pulleys whereby all of said propeller blades will be vibrated in unison.

15. 11. In a flying machine, the combination of a framework, a pair of lifting planes extending laterally therefrom, said planes being pivotally connected to said framework at the inner ends of their front edges, a pair of lever arms carried by said framework and extending forward and outward therefrom, and means for pivotally connecting the outer ends of said arms to said planes, the axis of said pivotal connection passing through the point of pivotal connection between the planes and the framework.

20. 12. In a flying machine, the combination of a framework, lifting planes extending laterally therefrom and connected thereto, flexible means secured to the ends of said framework and extending along the sides lengthwise of the same, means engaging said flexible means between the ends of said framework to hold the same spaced apart, and a pair of bars connected to said flexible means adjacent their inner ends and extending outward and forward from said framework and connected to said planes at their outer ends.

25. 13. In a flying machine, the combination of a framework, lifting planes pivotally connected thereto, flexible means secured to the opposite ends of the framework and extending longitudinally along the sides of the same, means for holding said flexible means spaced apart, arms secured to said flexible means and extending forward and outward of the framework, means for pivotally connecting the outer ends of said arms to said planes, and means connecting the inner ends of said arms to each other to permit the inner ends to be raised or lowered to adjust the said planes.

30. 14. In a flying machine, the combination of a framework, a rudder carried thereby

and extending rearward therefrom, a vertical spindle to which said rudder is secured, a cross bar carried by said spindle, a pair of rods pivotally secured on the ends of said cross bar and extending forward, a seat for the aviator pivotally mounted on the framework, a horizontal cross arm pivotally mounted upon said seat, and means for pivotally connecting said forwardly extending rods to the ends of said cross arm of the aviator's seat, whereby when the cross arm is turned the rudder can be operated.

35. 15. In a flying machine, the combination of a framework, a transverse bar, and flexible means uniting each end of said bar to the front and rear ends of said framework, said flexible means forming a quadrangular frame which is tiltable around a longitudinal axis.

40. 16. In a flying machine, the combination of a framework, a cross bar, flexible means connecting each end of said bar to the front and rear of the framework, wings movably connected to the framework, and means connecting said flexible means to each of said wings.

45. 17. In a flying machine, the combination of a framework, a cross bar, flexible means connecting each end of said bar to the front and rear of the framework, wings movably connected to the framework, means connecting said flexible means to each of said wings, and means for adjusting said means to enable the wings to be controlled.

50. 18. In a flying machine, the combination of a framework, a cross bar, flexible means connecting the ends of the cross bar to the front and rear of the framework, wings movably connected to the framework to enable their tips to be raised or lowered and the inclination of the wings to be varied, lever arms connected to said flexible means and to said wings, and means for connecting the inner ends of said lever arms adjustably together.

55. 19. In a flying machine, the combination of a framework, a cross bar, flexible means connecting the ends of said cross bar to the front and rear of the framework, wings movably connected to the framework so as to enable the tips of the wings to be raised and lowered and the inclination of the wings to be varied, an arm pivotally connected to each of the wings in line with said pivotal connection of each wing with the framework, said arms also being connected to the flexible means, and means for adjustably connecting the inner ends of said arms together to enable the wings to be controlled.

60. 20. In a flying machine, the combination of movable lifting planes, a lever arm for each of said lifting planes having one end pivotally secured thereto intermediate the ends of said wings, a fulcrum for each of

said lever arms between the ends thereof, and means engaging the opposite ends of said arms to enable the same to be adjusted.

21. In a flying machine, the combination of a framework, lifting planes extending laterally therefrom and connected thereto, yieldable means secured to the ends of said framework and extending along the sides lengthwise of the same, means engaging said yieldable means between the ends of the framework to hold the same spaced apart, a pair of bars connected to said yieldable means adjacent their inner ends, means for connecting said bars to the lifting planes at their outer ends, and means for connecting the inner ends of said bars together to cause said inner ends to be moved in unison.
- 15 22. In a flying machine, the combination

of a framework, lifting planes extending laterally therefrom and connected thereto, 20 yielding means secured to the ends of said framework and extending along the sides lengthwise of the same, means engaging said yielding means between the ends of the framework to hold the same apart, and 25 a pair of bars connected to said yielding means adjacent their inner ends and extending outward and connected to said planes at their outer ends.

In testimony whereof I have signed my 30 name to this specification in the presence of two subscribing witnesses.

WILLIAM LAFAYETTE QUICK.
